George L. Bennett INVENTOR

Frank J. Wentworth ATTORNEY.

UNITED STATES PATENT OFFICE.

GEORGE L. BENNETT, OF CLEVELAND HEIGHTS, OHIO.

SHEET WALL TILING.

Application filed March 24, 1926. Serial No. 96,917.

My invention relates to sheet wall tiling, and more particularly to the construction of such tiling and the manner of mounting different sections of same in relation to each other and to the walls of a building.

The wall tiling of my invention is made of sheet material, one surface of which is so formed and finished as to resemble ceramic tiles, or have any other desired finish. The construction is such that large sheets of this material may be secured in relation to the wall of a building and to adjacent sheets in a manner to avoid the presence of perceptible joints or crevices at the parting between adjacent sheets, while avoiding the necessity for the use of nails or fasteners passing through the sheets and having the heads thereof exposed.

In tiling embodying my invention, each sheet may not only be secured in position through the medium of concealed fasteners or attaching devices, but the construction and arrangement of the sheet, and the manner of mounting it, is such as to permit it to be quickly placed upon the wall of a building and to be accurately adjusted with relation to the adjacent sheet. The manner of mounting the sheets is such as to afford a substantially rigid backing at such frequent intervals as to prevent any possible buckling of the sheet resulting in a wavy effect at the surface thereof.

The fastening or attaching means form a part of the tile sheet, are so positioned as to afford a number of widely divergent points of support for the tile sheet, and are so constructed as to be anchored to the wall structure in a manner to prevent separation of the tile sheets therefrom without a breaking down of the wall itself adjacent the points thereof affording the anchorage for the fasteners.

In mounting tiling sheets embodying the invention no great nicety is required in the preparation of the wall for the reception of the tiling, the plastic condition of the portion of the wall co-operating with the fasteners, at the time of the mounting of the tiling sheets upon the wall, not only permitting a rapid mounting of the sheets in relation to the wall, but that slight adjustment of each sheet, as it is being mounted, necessary to secure a close fit at the parting line between adjoining sheets.

The invention consists primarily in sheet

wall tiling having one face thereof decorated and having permanently secured to the opposite face thereof a plurality of fastening devices projecting at an abrupt angle from the face to which they are attached and being of a length to penetrate the structure of the wall of a building, and firmly secure said sheet in position thereon without the presence of visible securing means at the decorative face thereof; and in such other novel features of construction and combination of parts as are hereinafter set forth and described, and more particularly pointed out in the claims hereto appended.

Referring to the drawings, Fig. 1 is a front view of a fragmentary portion of a wall covered with tiling embodying my invention;

Fig. 2 is a section upon the line 2—2 of Fig. 1 upon an enlarged scale;

Fig. 3 is a section similar to Fig. 2, but upon a much larger scale, showing the detailed construction of one form of fastener; and

Fig. 4 is a view similar to Fig. 3 illustrating a different manner of attaching the sheet of tiling to the wall.

Like letters refer to like parts throughout the several views.

In the accompanying drawings, the sheet wall tiling of my invention is shown as being composed of thin sheet material *a* having one face thereof, that to be exposed within a room, suitably decorated, and formed if desired, so as to resemble ceramic tiles, or to secure any other desired effect. These sheets will be of lengths to approximate the standard requirements for rooms of different heights, and will be of a width to be conveniently handled by the workmen.

Upon the back or undecorated face of this sheet *a* is a plurality of fastening devices *b* permanently secured to the sheet in any desired manner which will result in a desired substantially integral relation of the sheet and the fastening devices without causing these devices or the points of attachment of said devices to be conspicuously exposed at the decorated face of the sheet. Preferably the devices *b* are arranged in parallel horizontal rows, and are sufficient in number and so spaced, as to afford a multiplicity of points of attachment and support for the sheet after it has been mounted upon the wall.

The length and form of these devices *b* may vary to adapt them to different constructions of walls, those shown in the accompanying drawings being particularly 5 adapted for use where plaster strips are used for securing the tiling to the wall. The dimensions and configuration of the devices *b* may vary to permit them to penetrate different materials used in the wall structure 10 and to anchor firmly thereto, so as to hold the tile sheet firmly in position.

The fastening devices *b* shown in the drawings each consists of a flanged base *c* secured in any suitable manner to the back, 15 or undecorated, face of the sheet *a*, and provided with means, as the head *d* affording projections spaced from the sheet *a* which will resist the forcible withdrawal of the device from the wall structure with which 20 it co-operates, or to which it is anchored.

For convenience in assembling and shipping the tiling sheets the flanged base *c* and the head *d* may be made in two parts connected by means of screw threads shown 25 at *e*.

The fastening devices *b* extend at an abrupt angle from the face of the sheet *a* to which they are secured, it being desirable to have them extend from this surface at 30 substantially a right angle to facilitate the mounting of the sheets upon the wall structure.

As heretofore stated, a sheet wall tiling embodying my invention may be so constructed as to be used in connection with 35 various types of wall construction, the form of the invention shown in the drawings, being adapted for use with plaster strips extending along the wall and secured to a suitable rigid backing or ground.

In the accompanying drawings, the wall proper is shown at *f* and has strips *g* of plaster applied directly to the masonry of the wall or to the wooden studding of the wall 45 by means of lathing. The plaster forming the strips *g* may, when mounting the tiling, be plastic throughout as shown in Figs. 1 to 3, or may be composed of a strip *g'* of such plaster having a recess *h*, which may 50 be dovetailed or undercut as shown, formed therein, this strip being allowed to set and the recess *h* therein partially filled with fresh plaster *g*² which will be plastic when mounting the strips, preparatory to the mounting 55 of the tiling sheet with relation to the wall.

Tiling sheets *a* embodying my invention are made from thin gauge material, and the fastening devices *b* are secured thereto by welding, riveting or other similar methods 60 before the opposite face of the sheet has the decorations applied thereto, it being possible to place these decorations thereon by methods ordinarily employed in giving an enamel finish to metal sheets. The devices *b* 65 will, under no circumstances, project from

the face to which they are secured a distance sufficient to interfere with the applying of the decorations to the other face of the sheet, the maximum extent of the projection of these devices, when used with plaster finish 70 walls, being only about one-quarter to one-third of an inch.

In applying these sheets to, or mounting them upon, a wall, with a wall construction shown in Figs. 1 to 3 of the drawings, the strips of plaster are applied to the wall and while yet plastic, or before sufficient time has been allowed for the plaster to set, a tiling sheet is brought against this surface and the various devices *b* forced into the plastic material until the back of the sheet bears firmly 75 against the wall finish.

Pressure applied to the sheet *a* will cause the various devices *b* to penetrate the plastic facing without displacement of any material 80 quantity of the plaster, because of the small dimensions of the fasteners, such plaster as is displaced being forced back of the head *d* and closed upon the stem of the fastening device, as a result of pressure thereon from 85 the tiling sheet, so that as the plaster subsequently sets, a firm anchorage for the entire sheet is secured by means of the devices *b*.

In placing the sheet against the wall, the workman will bring one edge thereof with a close fit with relation to the edge of an adjacent, previously mounted sheet, it being possible to work the sheet in its entirety laterally to secure the desired close fit, since such working of the sheet will 90 cause no material disturbance of the plaster or no such displacement thereof as will not be compensated for by the readjustment of the plastic mass against which the sheet bears. The number and arrangement of the fastening devices, spurs or barbs *b* will cause 95 a distribution of the load of the sheet *a* in a manner to prevent any material settling of the sheet.

Before the sheet is mounted on the wall, the strips *g*—*g'*—*g*² of plaster are applied thereto and trued up, so that a rigid backing will be afforded to the sheet *a* adjacent its point of support, particularly after the plaster has set.

In Fig. 4, strips of plaster *g'* are applied to the wall, leaving elongated cavities therein, and the plaster thus applied allowed to set before the mounting of the tiling sheets thereon is undertaken. When these sheets are to be mounted, the cavities at *h* are partially filled with fresh plaster *g*² and the sheets are applied while the plaster in the cavities *h* is still plastic. This manner of mounting the sheets avoids possibility of disturbance of the plastic facing for the wall, in the event that the workman should press the sheet *a* too forcibly against the plastic facing, when mounting the sheet in the manner illustrated in Figs. 1 to 3 of the drawings. 100 105 110 115 120 125 130

It is also necessary when using the plastic strips g^2 in the cavities h , to allow for the displacement of the plaster in these cavities by the devices b , since any disturbance of the 5 plaster will be localized.

It is apparent that by securing the fastening devices b to the sheet a before the decorations are applied to these sheets, the enamel or other material of the decoration 10 will conceal all evidence of the presence of the fastening devices, and that the manner of mounting the sheets is such that a smooth continuous wall facing is secured with an almost imperceptible parting between the 15 different vertically extending sheets. This is especially true where the devices b are riveted on and ground flat on the finished surface.

The tiling sheets embodying my invention 20 have the advantage that they may be inexpensively installed, and when in position, are sanitary and act as a fire retardant.

The manner of mounting the sheets does not require any precision in the preparation 25 of the wall for such sheets, beyond the working up of the plaster or wood grounds to flat true surfaces. In fitting the sheets under these conditions, precision in locating the fastening devices b with relation to the 30 part of the wall with which they co-operate, is not necessary, since even if the plastic strips in the cavities h are used, there is sufficient latitude so that the workman in adjusting the sheet in relation to other sheets will 35 bring the fasteners into a position where they will penetrate some part of the plastic covering of the wall or the plastic material of said strips.

It is not my intention to limit the invention 40 to the precise details of construction shown in the accompanying drawings, it being apparent that such may be varied

without departing from the spirit and scope of the invention.

Having described the invention, what I 45 claim as new and desire to have protected by Letters Patent, is—

1. Sheet wall tiling having one face thereof decorated and having permanently secured to the opposite face thereof a plurality of fastening devices projecting at an abrupt angle from the face to which they are attached and being of a length to penetrate the structure of the wall of a building, and firmly secure said sheet in position thereon without the presence of visible securing means at the decorative face thereof. 55

2. Sheet wall tiling having one face thereof decorated, and a plurality of fastening devices each consisting of a flanged base, 60 permanently secured to the other face of said sheet, and a head having projections spaced away from said sheet sufficiently to penetrate and be anchored in a plaster facing of a wall of a building to secure said 65 sheet in position thereon without the presence of visible securing means at the decorated face thereof.

3. Sheet wall tiling having one face thereof decorated, and a plurality of fastening 70 devices each consisting of a flanged base permanently secured to the other face of said sheet, a head having projections spaced away from said sheet sufficiently to penetrate and 75 be anchored in the plaster facing of a wall of a building to secure said sheet in position thereon without the presence of visible securing means at the decorated face thereof, and means whereby said head may be removably connected with said flanged base. 80

In witness whereof I have hereunto affixed my signature this 18th day of March 1926.

GEORGE L. BENNETT.
